TYPEWRITING MACHINE

Ronald D. Dodge, Rochester, N. Y., assignor to International Business Machines Corporation, New York, N. Y., a corporation of New York

Application November 17, 1942, Serial No. 465,857

16 Claims. (Cl. 197—178)

This invention relates to typewriting machines. The principal object of the present invention is to provide an improved denominational tabulating mechanism.

Another object is to provide a denominational tabulating mechanism which is more suitable for operation by power.

An object is to provide a denominational tabulating mechanism which has a simpler means of determining the denominational stopping point of the carriage.

Another object is to provide a denominational tabulating mechanism which eliminates the necessity for a series of individual connections from the denominational keys adjacent the keyboard to the denominational counter stop mechanism behind the carriage.

An object is to provide a denominational tabulating mechanism which may be applied to a conventional power operated typewriter or, in fact, any typewriter, whether manually or power operated, without any substantial alteration in the typewriter.

An object is to provide a novel denominational selecting mechanism for tabulating mechanisms.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a vertical section through a power operated typewriting machine embodying the present invention.

Fig. 2 is a rear elevation of the tabulating mechanism.

Fig. 3 is a plan view of the tabulating mechanism.

Fig. 4 is a plan view of the mechanism associated with the denominational keys.

Fig. 5 is a front view, partly in section, of the mechanism shown in Fig. 4.

Fig. 6 is a vertical section on the line 6—6 in Fig. 5.

Fig. 7 is a detail view of the means for causing operation of the tabulating key when a denominational key is operated.

Fig. 8 is a large scale vertical section of certain parts of the tabulating mechanism.

Fig. 9 is a perspective view of the escapement release mechanism.

Fig. 10 is a detail view of the latch releasing cam unit.

Fig. 11 is a detail view showing the tabular lever in latched position.

Fig. 12 is a detail view on a large scale showing the relation of the tabular lever to the indexable counterstop.

The present invention has been shown in the drawings as applied to the well known "Electromatic" power operated typewriter, which also is known as the "International." This has been done purely as a convenience in description and it will be understood that the invention may be applied to other forms of power operated typewriters or to manually operated machines with only minor changes in the design of certain parts.

15 The reference numeral 10 designates the usual carriage rotatably supporting the platen 11 and mounted on the front rail 12 and rear rail 13 by means of the usual antifriction rollers 14. The rails 12 and 13 are rigidly supported on the base 15 of the machine and are spaced apart by braces 16 located at intervals along the rails 12, 13. The machine is also provided with a power roller 17 which rotates continuously in the direction of the arrow when the machine is in use. 20 The carriage is provided with the usual marginal stop rack 18 on which are mounted marginal stops, the reference numeral 19 in Fig. 1 designating the usual right hand marginal stop. The carriage also supports a tabular stop bar 20 on which are rotatably mounted the column stops 21. It is convenient in the present case to show the form of stop bar and tabular stop construction disclosed in Patent No. 2,157,053. For a reason which will be apparent hereinafter, the stop bar 20 has its faces inclined to the horizontal so that when the column stops 21 are set to active position by the usual setting lever 22 the edge 21a (Fig. 8) which usually cooperates with the tabular lever will be inclined slightly from the vertical. 25 The setting lever 22, when operated in a clockwise direction (Fig. 1) by means of the usual stop setting key as disclosed in the above patent, projects any stop 21 with which it may be in co-operation to the position shown in Fig. 8. The machine is also provided with a clearing lever 23 described in the aforementioned patent and operated by a stop clearing key which may be used to restore the stops 21 to the inactive position.

The machine is provided with a tabular lever 24 (Figs. 1, 2, 3, and 8), somewhat similar in general shape, mode of mounting, and method of actuation to the one disclosed in Patent No. 1,935,436. This lever 24 is pivotally mounted on a stud 25 (Fig. 2) supported by a U-shaped frame 55 26 mounted on the rear rail 13. The tabular lever

24 is formed with the usual short horizontal slot through which the stud 25 passes to enable the lever 24 to be pushed to the right a limited extent (Figs. 2 and 3). Normally the lever 24 is held in the left hand position, as in Figs. 2 and 3, by means of a spring 27 which is anchored to the right hand arm of the lever 24 and to a pin carried by the frame 26. The lever 24 is mounted in an open slot formed by two spaced portions of the frame 26 whereby the lever 24 may be rocked counterclockwise (Fig. 3) in a horizontal plane and also is capable of rocking on the stud 25 in a vertical plane (Fig. 2), as well as being capable of the aforesaid sliding movement. In the present case, only the horizontal pivotal movement and the sliding movement of the lever 24 is involved.

The horizontal movement of tabular lever 24 is effected by mechanism controlled by the tabulating key TK (Fig. 1). This key controls a cam unit 28 which is pivoted on the cross rod 29 and is rendered cooperative with power roller 17 in a well known way whenever the key is depressed. This causes cam unit 28 to be rocked clockwise (Fig. 1) by the power roller 17, thereby, through a link 30, rocking a bell crank 31 in the same direction. This bell crank is pivotally mounted on a cross rod 32 and is connected by a link 33 to a lever 34 (Figs. 2 and 3) pivoted at 35 on one arm of a normally stationary lever 36 supported by the rear rail 13 as in Patent No. 1,935,436. The aforesaid movement of the bell crank causes the upper end of the lever 34 to move rearwardly (Fig. 2), that is, upwardly with reference to Fig. 3. The lever 34 has its upper end engaging the side of lever 24 whereby said lever will be rocked counterclockwise in Fig. 3 whenever the tabulating key is depressed. This causes the left hand end of lever 24 (Figs. 2 and 3) to move forwardly (Fig. 2) or downwardly (Fig. 3).

Ordinarily a tooth 24a (Figs. 2 and 8), formed in the left hand end of the lever 24, cooperates directly with the column stops to arrest the carriage in various columnar positions as described in both the patents mentioned above. For the purpose of selectively arresting the carriage in different denominational positions there is interposed between the column stops 21 and the tooth 24a indexing mechanism including a counter stop controlled by denominational keys. This indexing mechanism includes a carrier 37 (Figs. 1, 2, 3, and 8) which may take the form of a sheet metal frame slidably mounted on a rod 38 extending parallel to the rear rail 13. The rod 38 is supported at one end by a plate 39 secured to one of the braces 16 as best shown in Fig. 1 while the other end of the rod is supported by a frame 40 also secured to the rear rail 13. Normally a spring 41 attached to the left hand side arm (Fig. 2) of the frame 37 and to the plate 39 holds carrier 37 in its right hand position (Figs. 2 and 3).

Secured to the frame or carrier 37 is an indexable counter stop member 42 which extends horizontally parallel with the rail 13 alongside the left hand end (Figs. 2 and 3) of the lever 24. This counter stop member has a counter stop element comprising a tooth 42a formed therein designed to move into the path of the set column stops 21 when the frame 37 is swung forwardly in Fig. 2 (downwardly in Fig. 3 and counterclockwise in Fig. 8). The counter stop member 42, in cooperation with the tabular lever 24, forms an indexing device for the counter stop tooth 42a and for this purpose is provided with teeth 42b

spaced at intervals to correspond with the spacing of the column stops 21. The number and spacing of the tooth spaces in the counter stop member 42 corresponds to the number of denominational keys with which the machine may be provided.

When the tabular lever 24 is rocked horizontally in the manner described above by the cam unit 28, the tooth 24a enters a selected one of the 10 spaces between the teeth 42b, according to the position of the carrier 37, and rocks the carrier 37 counterclockwise (Fig. 8) to carry the tooth 42a into the path of a set column stop 21. It is evident that the position in which the carriage is arrested will depend upon how far away from the 15 position of Fig. 3 the carrier 37 is displaced. Fig. 3 shows the carrier in the position designed to arrest the carriage at the decimal point printing position. This is also the position in which the carriage will be arrested if the tabulating key TK alone is depressed. In Fig. 3 the column stops 21 move to the right when the carriage is released during a tabulating operation whereby the nearest stop which is in set position to the 20 left of the tooth 42a will strike said tooth.

When the tabular lever 24 is rocked horizontally, as described above, to thrust the tooth 42a into the path of a column stop, it is held in operated position by a latch 43 pivoted on a stud 44 25 carried by the rear rail 13. This latch 43 is urged in a counterclockwise direction (Fig. 3) by torsion spring 43a (Fig. 11) coiled around the stud 44 which spring normally holds the edge 43b against the left hand vertical edge of an extension 24b (Fig. 2) of the tabular lever 24. When the latter is operated the spring 43a operating the latch 43 rocks the latter counterclockwise to the 30 position of Fig. 11. Counterclockwise movement of the latch 43 is limited by a stop portion 43c in 35 the latch engaging a lug 45a in a stop plate 45 secured to the rear rail 13 as most clearly shown in Fig. 11.

Means are provided to automatically release the latch 43 when the carriage is finally arrested 40 in the proper denominational position, which means is controlled by the horizontal sliding movement permitted the tabular lever 24 in consequence of the slotted mounting of said lever on stud 25. Secured to the side of lever 24 (Figs. 3 and 8) opposite the counter stop 42 is a frame piece 24c which is connected by a link 46 to an arm 47 secured to a vertical shaft 48 journaled in the frame 40. The lower end of the shaft 48 has an arm 49 connected by a link 50 to a trip lever 51 (Figs. 1 and 10) pivoted on the cross rod 32. This trip roller controls a cam unit 52 similar to the cam unit 28. The cam unit 52 is connected by a link 53 to one arm of a bell crank 54, the other arm of which is connected by a link 55 to an arm 56 (Figs. 2 and 3) secured to the lower end of a shaft 57 also journaled in the frame 40. The upper end of the shaft 57 is provided with an arm 58 connected by a link 59 to the latch 43.

When a tabulating movement takes place, one 55 of the set stops 21 will strike the tooth 42a and move the counter stop 42, the carrier 37 and the tabular lever 24 to the right (Figs. 2 and 3). This causes the link 46 to be drawn to the right 60 rocking arm 47, shaft 48 and arm 49 clockwise (Fig. 2). This thrusts the link 50 upwardly in Fig. 3 or to the right in Fig. 1 thereby releasing the cam unit 52 to enable said cam unit to be 65 operated by the power roller 17 in the usual way. Cam unit 52 rocks clockwise in Fig. 10, drawing down the link 53 and rocking bell crank lever 70 75

54 clockwise. This draws link 55 to the right in Fig. 1 or upwardly in Fig. 3 thereby rocking arm 56, shaft 57 and arm 58 counterclockwise. This draws the link 59 to the left in Fig. 3 and releases the latch 43, thereby permitting spring 27 to restore lever 24 to the position of Fig. 3.

When the tabular lever 24 is operated by the cam unit 28, the escapement mechanism is released automatically in the usual way. For this purpose there is provided the usual escapement release lever 60 pivoted on the top of the rear rail 13 (Figs. 1, 2, 3 and 9) and swinging in a horizontal plane. This release lever has a lug 60a engaged by the rear side (the left hand side, Fig. 1) of tabular lever 24. Lever 60 also has a portion 60b extending in the planes of the escapement pawls 61 (Fig. 9) whereby the pawls will be released whenever the release lever 60 is actuated clockwise (Fig. 3) by the tabular lever 24. Lever 60 also has a lug 60c engaged by the usual carriage-release bail 62 (Figs. 1 and 8) which is operated by the carriage release levers located on the ends of the carriage 10.

There are a number of conditions of rebound which must be satisfied in order to insure accurate operation of the tabulating mechanism. When the column stop 21 strikes tooth 42a (Fig. 3), there is a possibility of rebound of the column stop 21 to the left (Fig. 3) away from the tooth 42a. This is prevented by a rebound check pawl 63 pivoted on a stud 37a located on a bent-over lug formed in the carrier 37. The pawl 63 is actuated in a clockwise direction (Fig. 3) by a torsion spring 64 coiled around the stud 37a and hooked around the pawl 63. Clockwise rotation of the pawl 63 by the spring 64 is limited by a lug 63a which extends downwardly into the plane of the lug supporting the stud 37a.

As the set stop 21 travels to the right toward the tooth 42a it first engages the lower edge (Fig. 3) of the pawl 63 and rocks it slightly counterclockwise until, at the moment when said stop strikes the tooth 42a, the pawl 63 snaps behind the set stop and prevents the carriage from rebounding by trapping the set stop between the pawl 63 and tooth 42a.

There is also a possibility of the tabular lever 24 rebounding when the left hand end of the horizontal slot therein strikes the stud 25 in Fig. 2. In order to prevent this there is provided a second rebound pawl 65 (Fig. 3) pivoted on a stud 66 carried by the rear rail 13. This pawl 65 is located over a fixed stop lever 67 which is attached to the top of the rear rail 13 by means of the stud 66 and also by a stud 68. The stop lever 67 is formed with a stop lug 67a in the plane of the pawl 65 which is held against said stop lug by a torsion spring 69 coiled around the stud 66 and engaging both the edge of the pawl 65 and stud 68 so as to urge said pawl in a counterclockwise direction against lug 67a. When the tabular lever 24 is rocked by the cam unit 28 the extension 24d of frame piece 24c moves downwardly in Fig. 3 and rocks the pawl 65 clockwise. When the tabular lever 24 is moved horizontally to the right in Fig. 3 by the carriage, the extension 24d moves far enough to the right to clear the end of the pawl 65 which snaps upwardly in Fig. 3 to hold the tabular lever 24 in its horizontally displaced position. The pawl 65 is of sufficient length so that only a slight clearance space is provided to enable said pawl to clear the extension 24d when the tabular lever 24 has been moved far enough to engage the left hand end of the slot therein (Fig. 2).

with the stud 25. At the end of this movement of the lever the pawl 65 will be left holding lever 24 in its right hand position while the ratchet 43 will be holding the lever 24 in its horizontally rocked position. As soon as the pawl 65 is released, it reengages the rack 67a. When the latch 43 is released by the operation of the cam unit 28, as described above, the end of the pawl 65 prevents restoring movement of the lever 24 to the left (Fig. 3) until said lever has been restored clockwise (Fig. 3) by spring 27 far enough for the extension 24d to clear the end of the pawl 65. Spring 27 then draws lever 24 leftwardly to the position of Figs. 2 and 3.

The tooth 24a (Figs. 2 and 8) necessarily has a certain amount of backlash when engaging one of the tooth spaces in the counter stop member 42. This backlash will become worse with wear and may permit sufficient relative movement between tooth 24a and member 42 to prevent the escapement pawls from dropping into the proper tooth spaces in the escapement rack 10 (Fig. 1). This is particularly apt to occur where the mechanism is used on an elite machine or a machine having a finer pitch escapement rack. In order to prevent backlash there is provided an elongated spring plate 71 which is secured to a frame piece 24e fastened to the left hand end (Fig. 3) of the tabular lever 24. The spring plate 71 comprises a narrow flat strip extending horizontally in Figs. 2 and 3, with the flat side in a vertical plane, and is formed with a bent-over tooth 71a shaped somewhat similarly to the tooth 24a as will be apparent from the superimposition of the teeth (Figs. 3 and 12). When the tooth 42a is engaged with the counter stop member 42 the tooth 71a likewise enters a tooth space in said member causing the spring plate 71 to be flexed slightly in a clockwise direction (Fig. 3).

It will be noted in Fig. 8 that the teeth 42b in counter stop member 42 are cut so that the portions thereof cooperating with the tooth 71a are higher than the portions cooperating with tooth 24a. When tabular lever 24 is operated, tooth 71a enters a tooth space before tooth 42b and not only aligns the member 42 with respect to tooth 24a in case member 42 has not been accurately positioned, but also may have a slight tendency to push the member 42 to the left (Fig. 12) forcing the right face of tooth 24a into firm contact with the mating left hand face of the cooperating tooth 42b on the right. In this fashion member 42 and lever 24 are locked tightly together in a definite position determined by the cooperating pairs of the teeth 24a, 71a, 42b to prevent backlash.

The tabular lever 24 is formed with a lug 24f which cooperates with the marginal stops 18 (Fig. 1) to define the marginal positions of the carriage. The frame piece 24e is formed with a bent-over lug 24g which extends horizontally and downwardly on the side of the counter stop member 42 having the tooth 42a. This normally prevents the carrier 37 from rocking counterclockwise (Fig. 8) to carry tooth 42a into the path of the column stops while characters are being typed. Clockwise rotation of the carrier 37 from the position of Fig. 8 is prevented by a nose 67b (see Fig. 3 also) formed in the stop lever 67, which nose normally engages the side of the carrier 37 on which the counter stop member 42 is secured. Thus, in the position shown (Figs. 2, 3, and 8), the carrier 37 is free to slide horizon-

tally but cannot freely rock on the support rod 38 as an axis.

When the carrier 37 is rocked counterclockwise (Fig. 8) by the operation of the tabular lever 24, the tooth 24a pushes the side of the counter stop member 42 against the inner face of the lug 24g so that when the counter stop member 42 is locked with the tooth 42a in the path of the set column stops the carrier 37 will be held rigidly. This prevents the tooth 24a from being forced out of the tooth spaces in the counter stop member 42 from the shock of impact of the column stop with the tooth 42a.

In other words, as the tooth 24a moves horizontally to the left in Fig. 8, the lug 24g will move slightly away from the counter stop member 42 at first, but the pivotal movement of the carrier 37, effected by the continued movement to the left of the tooth 24a, will ultimately result in bringing the counter stop member 42a back into engagement with the lug 24g whereby any tendency of the tooth 24a to leave the tooth spaces and counter stop member 42 will result in pressure being applied to the lug 24g by said counter stop member.

The carrier 37 is shifted to the left from the positions of Figs. 2 and 3 different extents under control of differential mechanism which is located just behind and above the keyboard and is shown in Figs. 1 and 4 to 7. Mounted on the front plate 75 is a pair of brackets 76 supporting a cross rod 77 on which are pivoted the denominational keys 78. The latter extend through slots in plate 75 and are urged in a counterclockwise direction (Figs. 1 and 6) by means of springs 79 anchored to the upper edge of the plate 75. The keys may be spaced apart on the rod 77 by means of bushings 80 and are guided on their forward ends by means of key guide plates 81 of which there is one for each key. Each key guide plate is secured to plate 75 and has a vertical slot 81a through which passes the key 78.

Each key 78 is provided with a pair of anti-friction rollers 82, 83 which are rotatably mounted on pins 84 carried by bent-over lugs 85a formed in support plates 85 secured to the sides of the keys, the keys 78 being cut away to accommodate the lugs 85a and rollers 82, 83. The rollers 82 work in the slots 81a of the key guides 81. Counterclockwise movement of the keys 78 is limited by the engagement of said keys with the upper ends of the slots 81a.

The rollers 83, with the exception of the one for the extreme right hand key 78 (Figs. 4 and 5) cooperate with cams 86a formed in a differential plate 86 which is horizontally slideable behind the plate 75. Plate 86 is supported by anti-friction rollers 87 in horizontally aligned slots 86b formed in the differential plate 86. The rollers 87 are mounted on studs 88 secured to the plate 75. Normally the right hand end of the differential plate 86 is held against a spacing collar 89 by the effect of the spring 41 in Fig. 2 through a train of connections about to be described.

The cams 86a are of different degrees of inclination to the horizontal beginning with the steepest, associated with the second key 78 from the right (Fig. 5), and ending with the one having the least slope, associated with the extreme left hand key. There is no cam provided for the extreme right hand key 78 which corresponds to the decimal point position. The extreme left hand key, when depressed, by cooperation with its cam 86a causes the differential plate 86 to be displaced horizontally to the left the maxi-

mum distance, whereas the second key from the right causes said plate to be moved the minimum distance. The intervening keys cause the plate to be moved proportionate distances, each a different extent from the others.

When each key is depressed, its roller 83 first moves along the inclined surface of its cam 86a associated with such key until the differential plate 86 has moved the proper extent whereupon the roller enters the vertical slot 86c which is only slightly greater in width than the diameter of the roller 83. Thus, if the key is depressed rapidly the roller entering the slot 86c prevents the plate 86 from being moved violently a greater extent than necessary. Thus the rollers 83 in cooperation with the slots 86c prevent overthrow and rebound of the plate 86 with rapid operation of the denominational keys.

At its left hand end (Fig. 5) the differential plate 86 has a slot 86d into which extends a pin 89a on an arm 89 fixed to a shaft 90. The shaft 90 is journaled at its forward end in a bracket 91 carried by a fixed part of the framework and at its rear end in the frame 26 which, it will be recalled, supports the tabular lever 24. Thus horizontal movement of the differential plate 86 variable extents under the influence of the denominational keys 78 is communicated to the shaft 90.

In order to space the differential plate 86 away from the key guide plates 81 and to retain said plate on the rollers 87, there is provided at each end of plate 86 a pair of guide plates 92 (Figs. 4, 5, and 6) shaped like inverted T's secured to the rear face of the plate 75. Spacers 93 separate guide plates 92 from each other and from the plate 75.

Secured to the rear end of the shaft 90 is a hub 95 (Figs. 2 and 3) on which is secured an arm 96 having a pin 96a. Pivoted on a shoulder formed in the hub 95 is a pair of arms 97 having lugs 97a extending on opposite sides of a lever 98 also loosely mounted on the shoulder of hub 95, these parts being retained on the shoulder by a washer 100 (Fig. 2). The pin 96a, as shown in Fig. 2, extends between the two arms 97. A spring 101, anchored to the lugs 97a, draws the arms 97 into engagement with the pin 96a in which position the lugs 97a engage the parallel edges of the arm 98. Arm 98 is connected by a link 102 to the left hand side of the carrier 37 (Figs. 2 and 3). The clockwise rotation of shaft 90 (Fig. 5) produced by the variable movement of the differential plate 86 to the left in Fig. 5 causes counterclockwise rotation (Fig. 2) of the assembly comprising hub 95, the arm 96, arms 97 and 98, and spring 101 as a unit, thereby thrusting the link 102 to the left to position the carrier 37 commensurately with the extent of movement of the differential plate 86.

The assembly on the hub 95 is provided to relieve strain in the event that the keys 78 are depressed when the tabular lever 24 and the parts operated thereby, including the carrier 37, are already locked in one of their operated positions which would render the carrier 37 immovable along rod 38. On the other hand, while the denominational key 78 is being held down by the operator, the operation of the tabulating mechanism by the carriage results in a movement of the carrier 37 to the right along with the tabular lever 24 as explained above. This, of course, would tend to bend the link 102. In either case, 75 however, the assembly on the hub 95 permits the

arm 88 to yield in either direction and prevents damage to the parts.

After the plate 86 has been moved the full extent necessary by any key, it is desirable that the cam unit 28 be rendered operative to actuate the tabular lever 24 to cause the tooth 42a on the counter stop member 42 to be projected into the path of a column stop. This is effected by means of a bail 103 (Figs. 1, 4, and 6) journaled in the brackets 76 and extending underneath all of the keys 78. The bail 103 is provided with an extension 103a (Figs. 1, 5, and 7) overlying a bent-over lug 104a on a slide 104 mounted for vertical movement on the rear face of the plate 75. The slide 104 is formed with a nose 104b (Figs. 5 and 7) engaging the lever 105 of the tabulating key. The bail 103 is positioned so that it is engaged by a depressed key when the roller 83 for such key is about to ride off the cam 86a and enter the vertical slot 86c in the differential plate 86. By the time the roller 83 reaches the bottom of the slot 86c, the cam unit 28 will have been tripped by virtue of the slide 104 pushing down the key lever 105 of the tabulating key TK. The bail 103 is restored upon release of the denominational key by the usual spring 106 (Fig. 1) for restoring the tabulating key TK. This spring is strong enough to hold the tabulating key lever 105, the slide 104, and the bail 103 in the normal position of Fig. 1.

In Fig. 4, the faces of the keys are inscribed with large numbers to show the denominational positions corresponding to 1 million with comma keys representing the stopping points of the carriage in writing the commas, which ordinarily would be typed to set off every third figure to the left of the decimal point from the next higher denomination. In the actual writing of figures which are to be set off with commas, the comma keys 78 will not be needed since it will never be necessary to print a comma before writing the first significant digit. In machines for normal use in writing financial statements and other records involving amounts in dollars or in writing quantities the comma keys 78 may be omitted.

The extreme right hand key 78 corresponds to the decimal point position and is necessary where numerous quantities involving decimals alone are typed, since the decimal point will always be the starting point and must always be printed first in writing decimals. Conveniently, this can be the normal stopping point for simple columnar tabulating, that is where the matter written always begins in the first space on the left of a column several spaces wide, or in writing matter which must be indented. Depression of the decimal key has the same effect as depressing the tabulating key TK since this key does not move the differential plate 86 but merely operates bail 103 to trip key TK.

It is desirable to make provision for the writing in columnar form of numbers which will not be set off by means of commas. For this purpose the comma keys shown in Fig. 4 preferably should be provided in order to realize the full capacity of the denominational mechanism. The small numbers 1, 10, 100, and so on up to 100M (Fig. 4) represent units, tens, hundreds, thousands, ten thousands, millions, ten millions, one hundred millions, respectively.

One of the advantages of the denominational tabulating mechanism herein disclosed is that relatively few additional parts must be provided over the ones involved in the usual simple columnar tabulator to enable the attainment of

the denominational feature. Denominational tabulators as used at present on commercial machines require a separate counter stop for each denominational position and an independent train of connections between each counter stop and the corresponding denominational key. Each train of connections usually requires four or five separate parts besides the large and heavy framework for supporting them. These parts, in the standard machine, to a very considerable extent interfere with the servicing of the machine since the machines are much less accessible when equipped with the denominational tabulating mechanism on account of the fact that the connections to the denominational keys usually have to be located on the bottom of the machine and are in such a position as to obstruct access to other parts of the machine from the bottom.

Bearing in mind that the machine selected for purposes of illustration customarily is provided with the tabular lever 24 in cooperation directly with the column stops, it will be seen that the additional mechanism provided at the rear of the machine consists mainly of only the carrier 37, the indexable counter stop 42, and the connections from such carrier through the single shaft 90 to the keyboard. Since the shaft 90 offers little obstruction to the serviceman, it is evident that access to the machine for servicing is as good in the machine disclosed herein as in the standard machine having the simple columnar tabulator, it being unnecessary to provide ten sets of link connections from the denominational keys to the rear of the machine. Furthermore, the provision of ten counter stop elements and the necessarily complicated frame with associated parts to support and operate them on the rear of the machine is eliminated.

On the front of the machine, the invention disclosed herein has an advantage in that the entire denominational key mechanism may be removed as a unit by removing the plate 75 because of the pin and slot connection between the arm 88 and the plate 86. It is unnecessary to disrupt any operating connections by loosening screws or links in order to remove the key mechanism by removing this plate. In removing plate 75 from machines equipped with simple tabulators, it is usually merely necessary to remove the stencil and margin release control buttons and four screws for plate 75. Consequently access to the denominational key mechanism for servicing may be very quickly had without in any way affecting the rest of the machine. Furthermore, since the denominational key mechanism is located well above the keyboard, access to such mechanism may be had by merely removing the usual top cover over the type basket. When this cover is removed practically all of the parts of the denominational key mechanism are accessible for inspection, cleaning, and minor repairs.

Another advantage of the invention is that the denominational keys do not have to be held depressed until the carriage has come to rest. Usually the denominational counter stops of denominational tabulating mechanisms must be held in the path of the column stop by means of the denominational key. In the present case, this is not necessary because, upon the completion of the stroke of the denominational key, the mechanism actuated by the cam unit 28 is operated so rapidly that the counter stop 42 will be locked in indexed position by lever 24 before

the carriage even starts to move. Consequently, the operator need not do more than press the key down, and perhaps at the most, hold the key depressed a fraction of a second. This enables the operator to get her hands back over the keyboard ready for operation of a numerical key as soon as the carriage has come to rest. It is evident, therefore, that the machine may be operated more rapidly than is usually the case with conventional key-operated denominational tabulating mechanisms.

While there have been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine of the class described, in combination with the carriage, a column stop moved by the carriage, a counter stop movable into the path of the column stop; means to mount said counter stop for movement parallel with the path of movement of the column stop, said counter stop having a plurality of indexing teeth defining different denominational positions of said counter stop; an operating lever having an indexing tooth relative to which tooth said counter stop element moves, means to operate said lever to project said tooth into cooperation with said indexing teeth and to project said counter stop element into the path of the column stop, a series of selective devices representing different denominational stopping positions of the carriage in a column defined by said column stop, means controlled by said device for moving the counter stop element relative to said tooth to index said counter stop element to different denominational positions, and means controlled by said devices for operating said lever.

2. In a machine of the class described, in combination with the carriage, a column stop moved by the carriage, a counter stop movable into the path of the column stop and also differentially selectively movable parallel with the path of the column stop to different denominational positions, means to selectively move said stop; a member for moving said counter stop into the path of the column stop, said member being movable into engagement with the counter stop in any of its selectively set positions to lock said counter stop in said position; and means for operating said member.

3. In a machine of the class described, in combination with the carriage, a column stop moved by the carriage, a counter stop movable into the path of the column stop and also selectively movable parallel with the path of the column stop to any one of a plurality of denominational positions, and an operating member initially movable to engage said counter stop to lock said counter stop in its denominational set position and thereafter movable to project said counter stop into the path of the column stop.

4. In a machine of the class described, in combination with the carriage; a column stop carriage and a counter stop, one of said stops movable into the path of the other stop and also selectively movable parallel with the path of the column stop to any one of a plurality of denominational posi-

tions, one of said stops being movable by the carriage; and operating means engageable with said counter stop to lock said counter stop in its denominational set position and also operative to effect the moving of one stop into the path of the other, and means controlled by movement of the carriage for unlocking said counter stop.

5. In a machine of the class described, in combination with the carriage, a column stop moved by the carriage, a counter stop projectible into the path of the column stop and also selectively movable parallel of the path of the column stop to any one of a plurality of denominational positions, operating means engageable with said counter stop to lock said counter stop in its denominational set position and to project said counter stop into the path of the column stop, and a power operating device rendered operative upon engagement of the column stop with the counter stop for releasing the locking means.

6. In a machine of the class described, in combination with the carriage, a column stop moved by the carriage, a counter stop variably selectively displaceable parallel of the path of movement of the counter stop to different denominational positions, a member movable into engagement with the counter stop to lock said counter stop in its operative position, key controlled means to move said counter stop, and means automatically rendered operative when said counter stop is moved to a denominational position for rendering the locking means effective.

7. In a machine of the class described, in combination with the carriage, a column stop moved by the carriage, a counter stop variably selectively displaceable parallel of the path of movement of the counter stop to different denominational positions, a member movable into engagement with the counter stop to hold said counter stop in its operative position key controlled means to move said counter stop, means automatically rendered operative when said counter stop is moved to a denominational position for rendering the holding means effective, and means rendered operative upon engagement of the column stop with the counter stop for releasing the holding means.

8. In a machine of the class described, in combination with the carriage; a column stop and a counter stop, one movable by the carriage into engagement with the other to arrest the carriage in a columnar position; one of said stops also being initially movable parallel with the path of the carriage to a plurality of different positions representing different denominational stopping positions of the carriage, means to retain said stop in any of its denominational positions, means for mounting one of said stops for movement a limited extent upon impact with the other, means to effect the aforesaid movement to different denominational positions including a series of denominational selecting members, and means controlled by said limited movement for releasing the retaining means.

9. In a carriage tabulating mechanism, a column stop and a counter stop, one of which stops is mounted for movement into the path of the other to define a carriage stopping position by engagement of one stop with the other, one of said stops being selectively movable parallel with said path to different denominational positions; a series of denominational keys for moving said selectively movable stop to said denominational positions, means engageable with said selectively movable stop to lock the selectively movable stop in any of its denominational positions, and means

rendered operative by the operation of a denominational key to first actuate the locking means to lock said selectively movable stop in the denominational position defined by the operated key and thereafter effect the first named movement of said one stop into the path of the other stop.

10. In a carriage tabulating mechanism having a carriage moved stop and a stop which remains fixed while the carriage moves and is operated to arrest the carriage by impact of the carriage moved stop with the fixed stop, one of said stops being movable into a path containing the other stop, one of said stops acting as a counter stop and the other as a column stop, means to mount said counter stop for variable selective movement parallel with said path to any one of a plurality of different denominational positions, denominational key mechanism for selectively moving said counter stop to its different denominational positions, means to lock said counter stop in any of its denominational set positions, and power means rendered effective by the operation of any denominational key for actuating the locking means at the end of the setting movement of the counter stop.

11. In a carriage tabulating mechanism having a carriage moved stop and a stop which remains fixed while the carriage moves and arrests the carriage by impact of the carriage moved stop with the fixed stop, one of said stops being movable into a path containing the other stop, means to mount one of said stops for variable selective movement parallel with said path to any one of a plurality of different denominational positions, denominational key mechanism for selectively moving said selectively movable stop to its different denominational positions, means to lock said selectively movable stop in any of its denominational set positions, and power means for actuating the locking means at the end of the setting movement of the counter stop.

12. In a carriage tabulating mechanism having a carriage moved stop and a stop which remains fixed while the carriage moves and arrests the carriage by impact of the carriage moved stop with the fixed stop, one of said stops being movable into a path containing the other stop, means to mount one of said stops for variable selective movement parallel with said path to any one of a plurality of different denominational positions, denominational key mechanism for selectively moving said selectively movable stop to its different denominational positions, means to lock said selectively movable stop in any of its denominational set positions, power means rendered effective by the operation of any denominational key for actuating the locking means at the end of the setting movement of the selectively movable stop, and a second power means rendered effective by the impact of said stops for releasing said locking means.

13. In a carriage tabulating mechanism, a pair of coating stops, one moved by the carriage and the other remaining fixed during a tabulating movement of the carriage up to the time of impact between said stops, means to mount one of the stops for variable selective movement parallel

5 with the path of the carriage to different denominational positions, denominational selecting mechanism for variably selectively moving the selectively movable stop to said positions, an element engageable with said selectively movable stop to retain it in any of said positions and also operative to place one of said stops in the path of the other as a preliminary to a tabulating movement of the carriage, and means to operate said element to engage it with the selectively movable stop at the end of the variable setting movement of said variably movable stop.

14. In a carriage tabulating mechanism, a pair of coating stops, one moved by the carriage and the other remaining fixed during a tabulating movement of the carriage up to the time of an impact between said stops, means to mount one of the stops for variable selective movement parallel with the path of the carriage to different denominational positions, denominational selecting mechanism for variably selectively moving the selectively movable stop to said positions, an element engageable with said selectively movable stop to retain it in any of said positions and also operative to place one of said stops in the path of the other as a preliminary to a tabulating movement of the carriage, and means to operate said element at the end of the variable setting movement of said selectively movable stop, and power means rendered operative by impact between said stops for releasing said retaining means.

15. In a machine of the class described, in combination with the carriage, a column stop and a counter stop, one of which is moved by the carriage during a tabulating run of the carriage, said counter stop being variably selectively settable, in a path parallel with the path of the carriage moved stop, to any one of a plurality of denominational positions; denominational setting means for positioning said counter stop; and operating means for said counter stop, including an element engageable with said counter stop to hold it in its denominational set positions and at the same time to project one of said stops into the path of the other.

16. In a machine of the class described, in combination with the carriage, a column stop and a counter stop, one of which is moved by the carriage during a tabulating run of the carriage, said counter stop being variably selectively settable, in a path parallel with the path of the carriage moved stop, to any one of a plurality of denominational positions; denominational setting means for positioning said counter stop; operating means for said counter stop, including an element engageable with said counter stop to hold it in its denominational set positions and at the same time to project one of said stops into the path of the other, said operating means including a first power device for actuating said element into engagement with the counter stop; and a second power device rendered operative by impact between said stops for disengaging said element.

RONALD D. DODGE.
